UNITED STATES PATENT OFFICE.

JAMES FILLMORE MATTHEWS, OF ELRENO, OKLAHOMA TERRITORY, AS-SIGNOR OF ONE-HALF TO JAMES R. COLE, JR., AND CHRISTOPHER C. COLE, OF OKLAHOMA, OKLAHOMA TERRITORY.

COTTON-BALE-TIE BUCKLE.

SPECIFICATION forming part of Letters Patent No. 749,076, dated January 5, 1904.

Application filed April 17, 1903. Serial No. 153,002. (No model.)

To all whom it may concern:

Be it known that I, JAMES FILLMORE MATTHEWS, a citizen of the United States, residing at Elreno, in the county of Canadian and Territory of Oklahoma, have invented certain new and useful Improvements in Cotton-Bale-Tie Buckles, of which the following is a specification.

This invention relates to cotton-bale-tie buckles, and is designed particularly as an improvement over the similar device on which Patent No. 720,166 was issued to me February 10, 1903, my object in the present connection being to provide a buckle which will cause the tie after being slipped therein to automatically lock or "set" itself therein under the expansive pressure of the bale, this locking or setting action taking place invariably and without requiring any special preliminary twist on the part of the operator, as has been found necessary in the manipulation of the patented tie referred to, as otherwise the tie at times would reenter and frequently pass clear out of the entrance-slot.

With the object in view of providing a buckle from which it is impossible for the tie to accidentally withdraw after reaching the limit of movement which carries it up through said slot the invention consists in certain novel and peculiar features of construction and relation of parts, as hereinafter described and claimed, and in order that it may be fully understood reference is to be had to the accompanying drawings, in which—

Figure 1 represents a perspective view of the bale-tie buckle and of the contiguous ends of the tie, one of such ends being engaged with the buckle and the other end in position to enter the same. Fig. 2 is a face view of the buckle with the bale-tie ends in section and showing one end of the bale-tie in dotted lines, so as to disclose the relation of parts whereby it is impossible for such end to become accidentally disengaged from the tie.

In the said drawings, 1 designates the bale-tie buckle, of steel or equivalent metal and of oblong rectangular shape by preference.

2 is a central substantially oblong rectangular opening disposed with its long sides parallel with the corresponding outer mar-

gins, and such opening at one end is contracted in width by rounding its end and terminating one end of the rounded portion at a sufficient distance from the corresponding side of the opening to form a shoulder 4, disposed at right angles to the inner sides of the opening and a distance from the opposing end of the opening slightly exceeding the width of the bale tie or band. To be exact, the distance between said shoulder and opposing end is about one and one-sixteenth inches, so as to easily accommodate the bale tie or band in common use, which is about one inch in width.

The buckle at the side where the shoulder 4 occurs is cut away, so as to provide an entrance-slot 5 for opening 2, this slot in contour corresponding to that of the letter K. The slot furthermore inclines to the left or toward the rounded end of opening 2, so that its upper arm 6 shall extend at about right angles to the axis of said rounded portion, with the point 8 at the junction of said upper arm 6 and the lower arm 7 occupying approximately the same plane as the junction-point 9 of the straight slot-wall with the contiguous margin of opening 2.

One end of the tie or band 10 is secured to the non-slotted side of the buckle in the customary manner, and its opposite looped or free end to be secured to the buckle must be twisted or deflected to one side, as indicated by dotted lines, Fig. 2, and then slipped up through slot 5. By the time it is forced in said slot as far as possible one edge is bearing against the rounded end of opening 2 and its other edge has cleared the point 8. As soon as this disposition of the tie has been effected it is released, and at the same time the press-plunger (not shown) withdraws and permits the bale to expand and tension the tie or band, this tension causing the latter to untwist and impinge against arm 6, which it invariably strikes some distance above point 8, because the loop simultaneously moves to straighten or untwist itself at the same time it is retracted, as above explained. The tendency of the tie to retract and straighten continuing, the arm 6 serves to accelerate this straightening action by deflecting the engag-

ing end of the tie or band into the opening 2 and toward the square end of such opening, the rounded end of the opening coöperating in this action by deflecting the tie in the same 5 direction through engagement with its opposite edge. As a result the tie is automatically and invariably secured reliably to the buckle, as shown in full lines, Fig. 2, between shoulder 4 and the opposite end of the 10 opening and cannot accidentally, after once being disposed in the position shown in dotted lines, Fig. 2, slip back through slot 5.

From the above description it will be apparent that I have produced a bale-tie buckle 15 which embodies the feature of advantage enumerated as desirable in the statement of invention and which may be modified in minor particulars without departing from the principle of construction involved.

Having thus described the invention, what 20 I claim as new, and desire to secure by Letters Patent, is—

1. A bale-tie buckle having an opening contracted at one end, and provided with a shoul-

der to which one wall of the contracted portion slopes, and provided also in its side corresponding to said shoulder with an approximately K-shaped slot with its substantially straight wall nearest said shoulder.

2. A bale-tie buckle having an opening contracted at one end, and provided with a shoulder to which one wall of the contracted portion slopes, and provided also in its side corresponding to said shoulder with an approximately K-shaped slot having its substantially straight wall nearest said shoulder, and the junction-point of its arms in about the same inclined plane as that in which occurs the axis of the rounded end of the opening and the junction-point of the substantially straight 40 wall of the slot with the contiguous side of said opening.

In testimony whereof I affix my signature in the presence of two witnesses.

JAMES FILLMORE MATTHEWS.
